UNITED STATES PATENT OFFICE

139,716

DESIGN FOR A SOAP AND BRUSH HOLDER OR SIMILAR ARTICLE OF MANUFACTURE

George E. White, Bradenton, Fla.

Application September 25, 1944, Serial No. 115,442

Term of patent 14 years

(Cl. D4—3)

To all whom it may concern:

Be it known that I, George E. White, a citizen of the United States, residing at Bradenton, in the county of Manatee, State of Florida, have invented a new, original, and ornamental Design for a Soap and Brush Holder or Similar Article of Manufacture, of which the following is a specification, reference being had to the accompanying drawing, forming part thereof.

I claim:

The ornamental design for a soap and brush holder or similar article of manufacture, as shown.

GEORGE E. WHITE.
